No. 37,125.

Patented September 13, 1904.

UNITED STATES PATENT OFFICE.

CHARLES LOUIS JENNINGS, OF LEANDER, TEXAS.

DESIGN FOR A BADGE.

SPECIFICATION forming part of Design No. 37,125, dated September 13, 1904.

Application filed July 21, 1904. Serial No. 217,535. Term of patent 7 years.

To all whom it may concern:

Be it known that I, CHARLES LOUIS JENNINGS, a citizen of the United States, residing at Leander, in the county of Williamson and State of Texas, have invented a new, original, and ornamental Design for a Badge, which is shown in face or plan view in the accompanying drawing.

What I claim is—
The ornamental design for a badge, as so shown.

CHARLES LOUIS JENNINGS.
